PICKER CHECK FOR LOOMS

Edward C. Nichols, Upton, Mass., assignor to
 Draper Corporation, Hopedale, Mass., a corporation of Maine

Application April 13, 1948, Serial No. 20,673

10 Claims. (Cl. 139—164)

1

This application pertains to an invention in looms, and more particularly, to means for arresting or checking the picker and for preventing rebound of the loom shuttle.

It is a general object of the invention to provide an improved means for checking the movement of the picker and picker stick of a loom as these parts approach the end of their stroke and to prevent or reduce to a minimum the tendency of the shuttle to rebound from the end of the shuttle box. Along with this general object, it is a further object to do away with the conventional check straps and their attendant supporting and adjusting means, all of which add materially to the mass reciprocable with the lay.

It is a more specific object to devise a relatively compact, light device which shall be readily applicable to the lay ends and which shall be engaged by the picker itself for checking its return and for thereafter, upon contact between the shuttle and picker, absorbing the kinetic energy of the rapidly moving shuttle to stop the parts with the shuttle properly boxed and with substantially no rebound. It is a further object to provide for centering the picker so it may be positioned centrally of the shuttle path and to prevent engagement between the picker stick and the sides of that slot within which it travels.

Another object of the invention is that of providing a universal mounting for one of the picker checking members so that it will always engage the picker under uniform conditions and with evenly distributed pressure. A further object is that of devising an adjustment which, with the universal mounting, may be employed to set the check means for different conditions of operation. Other objects will become apparent from the following disclosure.

The conventional picker and picker stick checking means employs leather or similar straps which are adjustably retained beneath the lay and which are engaged by the picker stick as it moves in either direction. These check straps contribute considerably to the cost of a loom operation since they must be replaced frequently. Also, their intended function is not well served when they are subjected to varying conditions of humidity. They wear rapidly and thus adjustments must follow frequently. The check strap brackets and attendant adjusting means are relatively heavy and add considerably to the mass of the reciprocating lay which is already more bulky than is desired.

With the above mentioned or other inadequacies of the conventional check straps in mind,

2

the present invention is directed toward a light and simple mechanism which acts directly upon the picker itself, and which is carried at the lay adjacent the outer ends of the front and rear shuttle box plates. At the rear side of the shuttle box and adjacent the binder pivot is fixed, preferably in an adjustable manner, a plate extending parallel to that side of the picker and in the same direction as the shuttle movement along the lay. 5 This plate functions to oppose the forces directed against it through the picker by a resiliently actuated, complementary check member. It also serves in cooperation with other parts, to position the picker at the center line of the path of shuttle flight.

At the front of the shuttle box and at a position opposite the relatively fixed plate is adjustably attached to a convenient portion of the lay or box mechanism a complementary pressure member. 10 This member preferably includes a rigidly attached base to which is connected for a limited amount of movement a movable presser member. Resilient means such as springs is interposed between the base and presser member and serves to 15 urge the latter into engagement with the picker.

While the invention in one of its broader aspects contemplates the employment of any resilient means in combination with the universally mounted presser member, it is preferred that 20 separate and independently adjustable resilient means be utilized one adjacent the picker checking point along the movable presser member, and the other close to that point at which the picker is finally stopped after the shuttle has been boxed. 25 By properly adjusting the amount of force to be exerted at each point, it is possible to regulate the picker checking and the absorption of energy expended by the moving shuttle as it is arrested, so that the parts always stop at the end of the lay 30 with virtually no tendency to rebound.

The device is preferably constructed entirely from metal and thus has a life comparable to that of the other more permanent loom parts. At that time when the picker stick is subjected to its most 35 rigorous action, it is guided centrally of its slot and of contact with the sides thereof. The picker itself is steadied in its movement and is held at each side so as to resist the tendency of the shuttle spur to split or otherwise injure it.

50 The invention and one modification thereof will be described in greater detail by reference to the accompanying figures of drawing wherein:

Fig. 1 is a plan view of a portion of a lay end, shuttle, picker and shuttle box to which the invention is applied as shown.

Fig. 2 is a front elevation of the mechanism of Fig. 1.

Fig. 3 is a section taken horizontally of the device at line 3—3, Fig. 2.

Fig. 4 is a transverse section taken at line 4—4, Fig. 1.

Fig. 5 is a perspective view of one form of the fixed picker engaging plate.

Fig. 6 is an exploded view of the universally mounted, movable presser member base and 10 presser plate.

Fig. 7 is a section of part of the movable presser member illustrating a modified form of spring device.

Now referring to Figs. 1, 2 and 3, a preferred form of the invention has been applied to a lay end of a typical loom of which only enough of the parts intimately associated with the picker check are shown as are necessary to a full understanding of the invention. A picker 10 is attached to the end of a picker stick 11 pivoted at a parallel motion at the base of the loom and actuated in a manner not shown or described here since it is not necessary to an understanding of this invention. The picker stick is loosely guided in a slot 12 at the lay end generally indicated by numeral 13. A front box plate 14 is attached in the usual way, while the rear box plate including a binder 15 pivoted at 16 completes the box structure within which the shuttle 17 is received after being picked from the opposite side of the loom, and from which it is ejected on its return pick by the stick 11 and picker 10.

The shuttle is provided with a spur 18 engageable within a conical recess at the inner end of picker 10. In normal operation the picker stick is forcefully moved from its outer position in which it bears against stop 19 at the end of slot 12 and through the intermediary of picker 10, rapidly accelerates the shuttle to start it on its flight to the opposite side of the loom. The stick 11 is checked or stopped on its inner beat or stroke by any satisfactory mechanism, whereupon it is then returned outwardly by the usual heel strap or other mechanism (not shown).

On the return beat of the picker stick it is desirable to check it at a point spaced a short distance, e. g., about two inches, more or less, from the stop 19. When the returning shuttle strikes the picker it moves it toward the end of the lay or until the stick is lodged against stop 19. It is the function of the novel means hereinafter to be described to stop the picker and its stick at the first so-called picker check position, and then to prevent rebound as the parts move to the lay end, by absorbing the kinetic energy in the shuttle so that it will be fully boxed and will remain in that position, i. e., will not rebound.

As shown in Figs. 1, 3 and 5, the novel check means comprises, at the rear or back of the lay, a relatively fixed, but preferably adjustable, guide plate 20 having a curved inner end 21 and an angularly directed extension 22 by which it is attached to some convenient portion of the lay or back plate.

Here an extending lug 23 has been cast on the back box plate extension 24 and is drilled for bolts 25 which pass through slots 26 in the extension 22. The guide plate 20 is adjustable by loosening bolts 25 after which it may be locked in properly adjusted position. Extension 22 has an aperture 27 cut therein to provide clearance for the binder pivot 16.

The movable presser plate 28, as shown in Figs. 1, 2, 3, 4, and 6, is symmetrically formed about

center line 4—4, Fig. 1. That makes it possible to use units constructed identically at either side of the loom. Base 29 is slotted at 30 and is adjustably clamped in position on lay end 13 by bolts or screws 31. These permit adjustment of the position of the entire unit.

Base 29 has projecting side extensions 32 and 33 terminating at their upper, outer end in lugs 34 and 35. When assembled by placing plate 28 in position and then sliding base 29 into place so that the extensions 32 and 33 enter grooves formed between the receding portions 36 and 37 and the in-turned ends 38 and 39, the two parts are locked together, although presser plate 28 will be free to move through a limited extent. That movement is not restricted, within limits, in any direction, and thus is termed a universal one.

The base casting 29 is hollowed out to house 20 the springs 40 and 41 which are under compression between the plate 28 and a yoke 42. The presser plate itself is maintained at proper height by contact of the end portions thereof with the underlying portion of the lay end or, as here shown, an adapter piece 13' attached above the lay end.

Springs 40 and 41 are adjusted by moving yoke 42 in or out as adjusting screws 43, threaded into the yoke and bearing at their heads in recesses 44, are turned in the appropriate direction. Holes 30 entering the recesses from the outer side of the base permit engagement of the screw heads by a wrench or other tool.

A locking screw 45 passes through the base casting from the outside and when drawn up, binds or 35 locks the yoke into which it is threaded. There is enough angular displacement of the yoke possible so that the springs may be adjusted to different values, so that the checking action controlled by the inner spring 41 may be set independently of 40 that of the outer spring which affects that end of the presser plate more intimately associated with the prevention of rebound.

While the two springs control the two functions 45 above mentioned independently to an extent, it is a fact that each function is affected to some extent by both springs. The picker is stopped or checked in approximately the position of Fig. 1, and at that point the inner spring 41 is dominant. The contact of the shuttle then 50 drives the picker to its endmost position during which time both springs become involved and the outer one 40 to an increasing extent as the movement progresses. With the correct setting 55 of the springs it is possible to check the picker far enough from its extreme outward position, Fig. 3, so that with the resistance offered, the parts will stop without rebound and with the shuttle completely boxed.

The base casting is arched upwardly as at 46 to encase the springs and attendant parts and to present a relatively smooth exterior so that the 60 filling or other yarns may not become intangled therewith.

Now referring to Fig. 7, a modification is shown 65 in which the spring adjustment is not an individual one. Here the parts corresponding to those above described have been designated by the same numerals primed. Springs 47 and 48 bear against presser plate 28, being forced in that 70 direction by a yoke 49. The springs are maintained in position by pins 50 and 51 riveted or otherwise inserted in the yoke. An adjusting bolt 52 passes through yoke 49 and into the base 29 and by it, the yoke may be drawn in to increase tension or vice versa. Here the entire

unit may be adjusted or the springs may be simultaneously tensioned. By combinations of these settings the picker function may be controlled so that the shuttle will not rebound and will box as intended.

The preferred form of the invention contemplates placing the so-called fixed member at the back of the lay end and the movable member at the front. Obviously, that arrangement of parts may be reversed if desired. The term "movable member" includes the base, the movable presser plate, springs, etc., but is generally designated as movable to distinguish it from the fixed plate which is only moved incidental to adjustment. While, as described, the movable member is reversible so as to be applicable to either end, that is not wholly essential and may be changed for reasons, in which event separate "right" and "left" units are utilized.

It has been found in practice that the plates 20 and 28 function well if made from a relatively hard, smoothly polished metal, for example, steel, but if desired other materials may be used, or metal may be faced with a satisfactory friction material.

Here the device has been adapted for use with one type of picker, but it is well suited to use with other forms of pickers, and modifications necessary for that purpose will readily occur to those skilled in the art.

While one preferred embodiment and a modification of the invention have been disclosed, it is to be understood that the inventive concept may be carried out in a number of ways. This application is, therefore, not to be limited to the precise details described, but is intended to cover all variations and modifications thereof falling within the spirit of the invention and the scope of the claims.

I claim:

1. In a loom having a lay, a shuttle box at the end of said lay, a shuttle, means for propelling the shuttle along said lay including a picker stick and a picker and a slot in said lay within which said picker stick is guided, means for checking said picker and picker stick as they approach the end of the slot in the lay and for preventing rebound of the shuttle from the end of the shuttle box which comprises a relatively fixed plate at one side of and adjacent the outer end of said shuttle box and disposed at a position to engage one side of the picker when it approaches the end of its stroke, means for adjusting said fixed plate laterally of the slot and into parallelism with the direction of shuttle flight, and a relatively movable presser member at the opposite side of the shuttle box, said member being opposed to and universally mounted for movement to and from the fixed member so that the picker engaging face thereof may exert a substantially uniform pressure against the face of the picker engaged thereby, and resilient means for urging said member into engagement with the picker.

2. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member being sub-

stantially coextensive in length with said fixed plate and supported for limited movement universally so that the picker engaging face thereof may exert a substantially uniform pressure against the picker, and means for urging said member into engagement with the picker comprising two tensioned springs spaced lengthwise of the member.

3. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member comprising a base portion adjustably attached to the lay end and a presser plate connected to said base portion for limited universal movement relatively thereto so that the picker engaging face thereof may exert a substantially uniform pressure against the picker, and spring means for forcing said presser plate away from the base portion and toward the picker and means for varying the tension in said spring means.

4. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member comprising a base portion and means for adjustably attaching it to the lay end, and a presser plate having a centrally disposed flat picker engaging surface from which extends in at least one direction an angularly receding portion, said plate having inturned ends by which it is loosely interlocked with complementary engaging members on said base, and spaced adjustable spring means between said base and presser plate for urging it toward the said fixed plate and into contact with the face of the picker.

5. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member comprising a base portion and means for attaching it to the lay end and providing adjustment laterally thereof, and a presser plate having a central flat picker engaging surface from which extend symmetrically in either direction, angularly receding portions having inturned ends by which the presser is loosely interlocked with complementary engaging members on said base, and spaced adjustable spring means between said base and presser plate for urging it toward the said fixed plate and into contact with the face of the picker.

6. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member comprising a base portion attached to the lay end and a presser plate connected to said base portion for limited universal movement relatively thereto, and spring means for forcing said presser plate into contact with the picker including two spaced springs, one adjacent either end of the member, and means for effecting independent adjustment of the tension in said springs.

7. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member comprising a base portion attached to the lay end and a presser plate connected to said base portion for limited universal movement relatively thereto, and spring means for forcing said presser plate into contact with the picker including two spaced springs, means for adjusting the tension in each spring independently including a yoke, threaded adjusting screws for positioning said yoke and a locking screw for maintaining said yoke in a set position.

8. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member comprising a base portion attached to the lay end and a presser plate connected to said base portion for limited universal movement relatively thereto, and spring means for forcing said presser plate into contact with the picker including two spaced springs,

means for adjusting the tension in said springs including a yoke against which said springs bear at one end, centering pins projecting from said yoke for guiding the springs, and an adjusting means centrally positioned between the springs for drawing the yoke inwardly.

9. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, positioned so that the picker engaging face thereof may bear against the opposite side of the picker, and spring means for urging said member into contact with the picker comprising two springs spaced apart and bearing at points adjacent the ends of the member, and means for effecting independent adjustment of the tension in each said spring.

10. In a loom having a lay, a shuttle box at the end of said lay, a shuttle and means for propelling the shuttle along said lay including a picker stick and a picker, means for checking said picker and picker stick and for preventing rebound of the shuttle which comprises a relatively fixed plate at one side of and adjacent the outer end of said shuttle box and disposed at a position to engage one side of the picker when it approaches the end of its stroke, and a relatively movable presser member at the opposite side of the shuttle box, said member being coextensive with and opposed to said relatively fixed plate, a mounting means for said relatively movable presser member for restraining it in the direction of picker movement, but permitting a limited universal motion thereof laterally of that direction so that the picker engaging face thereof may exert a substantially uniform pressure against the picker, and resilient means for urging said member into engagement with the picker.

EDWARD C. NICHOLS.
